ATTORNEY

UNITED STATES PATENT OFFICE

CARL OTTO, OF HELLERUP, DENMARK

COKE OVEN

Application filed March 20, 1925. Serial No. 17,101.

My invention relates to a burner-flue construction for coke ovens with horizontal or vertical oven chambers, and particularly to such a burner-flue which will produce a uniform heating in a vertical direction of the flue when the oven is heated with strong gas.

One of the objects of the invention is to avoid eddies which might otherwise occur between the gas and air supplied and thus to 10 avoid a quick combustion and an overheating of the lower part of the oven chamber as well as to avoid eddying of the gas toward the walls of the heating flue which would cause a deposit of carbon upon the flue and an 15 overheating of this portion of the flue wall. The carbon deposit burns with difficulty and such burning can be accomplished only by supplying a large amount of excess air, which, however, leads to a shortening of the 20 flame and an overheating of the lower part of the oven chamber.

In accordance with the invention, the burner opening is raised to such a height in the flue and the air is supplied at the bottom 25 of the flue at some distance below the burner opening in such a way that the air supply is slowed up and the air has time to rise in the space in the flue between the burner and the flue walls, so as to produce a uniform, 30 eddy-free, upward flow and thereupon to uniformly supply the gas escaping from the burner. In the best embodiment of the invention, the gas burner is tapered toward its 35 burner end to avoid eddies and to guide the air to the burner.

With the above and other objects in view, my invention consists in the parts, improvements and combinations more fully pointed out hereinafter.

40 Referring now to the drawings:

Figure 1, is a vertical cross-section of a portion of a horizontal coke oven, showing my improved burner-flue construction.

45 Figure 2, is a vertical cross-section taken at right-angles to Figure 1.

Figure 3, is a detailed cross-sectional view thru the burner-flue construction, on the line 3—3 of Figure 1, and,

50 Figure 4, is a horizontal-cross-section on line 4—4 of Figure 3.

The horizontal coke oven is provided with horizontal coking chambers 1, at each side of which heating flues 2, are arranged. Regenerators 3, preheat the air, or one regenerator may be used to preheat air and another regenerator may preheat weak gas, if 55 desired.

The oven is shown as provided with supports 4, thus forming an underburner oven. Strong gas is supplied to the burners 5, thru 60 vertical pipes 6, which, in turn, communicate with horizontal gas supply pipes 7, supplied by gas main 8, arranged in the underburner part of the oven.

In accordance with the invention, the burner top 9, is arranged within and above the bottom of the flues 2. As shown, the flues are of the same length. The burner in the heating flue is kept within heating proximity of and projects above the bottom of the coking chamber. Preheated air coming from the regenerators 3, passes into the bottom of the flue thru passageways 10, 11, arranged on each side of the burner, and passes upwardly in uniformly flowing streams on each side of the burner. When desired, air may be supplied to the heating zone thru one passageway 10, and weak gas thru the other passageway 11, supplied from its respective regenerator, the strong gas burner 5, being then 75 not used. The burner is separated from the side of the flue walls, thus forming a space between the burner and the walls to which the air for the burner is supplied.

When burning with strong gas thru burner 5, the air supplied from both passageways will be free from eddies when it reaches the top 9 of the burner 5, by reason of the long travel of the air before it reaches the burner top. Inclined guiding walls 12, 13, are provided at the discharge end of the air passageways 10 and 11, so as to guide the air upwardly. The strong gas burner 5, is made tapering at 14, toward its top so as to guide 90 the air to the burner top 9, without causing eddies. The upper portion of the strong gas burner 5, may be made removable by providing a joint 15, between the upper portion of the burner and its base. This upper portion 95 100

may then be removed by inserting a rod into flue holes 16.

As shown in Figures 1 and 2, the strong gas burners may be alternately high and low burners which extend to different heights from and above the bottoms of the various flues, and may be in successive flues, so as to provide a uniform heating for the lower part of the oven chamber.

10 Having thus described the invention and its operation, it will be understood that changes may be made in carrying the invention into effect, without departing from the principle thereof.

15 What I claim and desire to secure by Letters Patent is:

1. In a coke oven heating wall having a plurality of vertical combustion flues, each of the same length, the bottoms of the flues being on substantially the same level, the combination with said flues of a plurality of fuel gas burners the said burners extending to different heights above the bottoms of the flues each burner projecting into its flue above the 25 flue bottom, and means for supplying air to each of said flues, below its burner.

2. In a coke oven heating wall having a plurality of vertical combustion flues in a row, each of the same length, the bottoms of the 30 flues being on substantially the same level, the combination with said flues, of a plurality of alternate high and low strong gas burners said burners extending to different heights above the bottoms of successive flues 35 and projecting into said flues from and above the bottoms thereof, and means for supplying air at the bottom of each of said flues.

3. In a coke oven heating wall having a plurality of vertical combustion flues, each 40 of the same length, the bottoms of the flues being on substantially the same level, the combination with said flues, of a plurality of strong gas burners extending to different heights in said flues, said burners being tapered at their sides toward their tops and projecting into said flues from and above the bottoms thereof, and means for supplying air at the bottom of each of said flues.

4. In a coke oven heating wall having a 50 plurality of vertical combustion flues, each of the same length, the bottoms of the flues being on substantially the same level, the combination with said flues of a plurality of strong gas burners extending to different heights in 55 said flues and projecting into the said flues from and above the bottoms thereof, and means for separately supplying weak gas and air at the bottom of each of said flues.

5. In a coke oven heating wall having a 60 plurality of vertical combustion flues, each of the same length, the bottoms of the flues being on substantially the same level, the combination with said flues of a plurality of strong gas burners extending to different 65 heights in said flues and projecting into the

said flues above the bottoms thereof, each of said burners having a removable tip-portion, the top of the oven above said flues being provided with holes thru which the tip-portion may be removed, and means for supplying air at the bottom of each of said flues.

6. In a coke oven heating wall having a plurality of vertical combustion flues, each of the same length, the bottoms of the flues being on substantially the same level, the combination with said flues of a plurality of strong gas burners, projecting into said flues above the bottoms thereof, the said strong gas burners being separated from the walls of said flues, thereby providing spaces between the burners and the flue walls, and means for supplying air at the bottom of each

70

75 of said flues, the air supplying means being provided with a discharging opening, and an inclined wall arranged in each of the flues at the said discharging opening, so as to guide the air toward the burner tops.

7. In a coke oven heating wall having a plurality of vertical combustion flues, each of the same length, the bottoms of the flues being on substantially the same level, the combination with said flues, of a plurality of strong gas burners projecting into said flues above the bottoms thereof, said burners being separated from the walls of said flues,

80

85 thereby providing spaces between the burners and the flue walls, and means for separately supplying weak gas and air at the bottom of each of said flues, the weak gas supplying means being provided with a discharging opening at the one side of each burner and the air supply being provided with a discharging opening at the opposite side of each burner, and inclined walls arranged in each of the flues at the said discharging opening, so as to guide the air toward the burner tops.

90

95 8. In a coke oven having a plurality of vertical combustion flues arranged in a row, in a heating wall of the oven, with the bottoms of the flues at the same level, the combination with said flues of a plurality of strong gas burners projecting into the lower portions of said flues from and above the flue bottoms, some of the burners extending to

100

105 one height above their flue bottoms and other burners extending to a lesser height above their flue bottoms, and means for supplying air to the said burners.

105

110 9. In a coke oven having a plurality of vertical combustion flues arranged in a row in a heating wall of the oven, with the bottoms of the flues at the same level and the flues being of the same length, the combination with said flues of a plurality of strong gas burners projecting into the lower portions of said flues from and above the flue bottoms, some of the burners extending to one height above their flue bottoms and other burners extending to a lesser height above their flue bottoms, and means for supplying air to the said burners.

110

120

125

130

10. In a coke oven having a plurality of vertical combustion flues arranged in a row, in a heating wall of the oven, with the bottoms of the flues at the same level, and the flues being of the same length, the combination with said flues of a plurality of alternate high and low strong gas burners projecting into the lower portions of successive flues, from and above the flue bottoms, and means for supplying air to the said burners.

In witness whereof, I have signed my name to this specification.

CARL OTTO.
